UNITED STATES PATENT OFFICE.

WILLIAM ERNEST WALKER, OF NEW ORLEANS, LOUISIANA; J. MORT WALKER
ADMINISTRATOR OF SAID WILLIAM ERNEST WALKER, DECEASED.

ORTHODONTIA APPLIANCE.

1,142,467.

Specification of Letters Patent. Patented June 8, 1915.

Application filed December 30, 1912. Serial No. 739,382.

To all whom it may concern:

Be it known that I, WILLIAM ERNEST WALKER, a citizen of the United States, and resident of New Orleans, in the parish of 5 Orleans and State of Louisiana, have invented certain new and useful Improvements in Orthodontia Appliances, of which the following is a specification.

This application is a division in part of 10 my co-pending application, Serial No. 654,769.

This invention relates to an improved treatment of the teeth, individually or in groups, as for instance by influencing the 15 tooth or teeth for the purpose of correcting existing or impending irregularities, either in the immediate tooth treated or in a developing tooth so located as to be improperly influenced by an existing tooth or by abnormal force; or for the purpose of 20 correcting existing or impending abnormal facial lines resulting from mal-development or mal-position of the teeth or jaws; also to the treatment of the jaws for the purpose 25 of correcting their relative position and developing proper occlusion.

The invention consists primarily in the art of orthodontia or bringing to bear upon the tooth or teeth to be affected individually, 30 a force or forces of a relatively light but persistent or continuing character, either for localizing natural forces, such as from occlusion, or by simulating the forces which influence the positioning of the teeth as they 35 develop in nature, as by applying the force or forces such as are produced by light, resilient extensions from a carrying member.

One feature of the present division of my invention relates to means for securing anchorage of the device upon the teeth, particularly when, for considerations of hygiene, comfort and appearance, carrying bows are to be located out of the horizontal areas of the dental arches so as to overlie 45 the gums. According to this feature of the invention, anchorage for the carrying member or bow is attained either wholly or partially by means of a combined positioning and gripping member constructed on the 50 lingual side to embrace the crown of the tooth close to the gum, with connecting members extending across the inter-cuspal

notches, and on the buccal or labial side, gripping ends extending into the embrasures below the bulge; these gripping ends being 55 preferably in the form of claws formed either directly upon the ends of the connecting members or upon ends which are made to project from an intermediate portion of a closed loop on the gripping side. The em- 60 bracing portion on the lingual side of the tooth may likewise consist of a pair of gripping claws extending from the closed loop on that side into the embrasures beneath the approximal bulge; or this embracing portion may be provided by so forming the closed loop itself, that it extends downward 65 and embraces the lingual bulge near the gum. With the gripping claws formed directly upon the connecting members, an anchoring grip is provided which has an open face on the labial or buccal side of the tooth which is relatively inconspicuous and correspondingly advantageous, particularly when anchorage is required on anterior teeth. In 70 either construction of the gripping claws, the grip is maintained or released mainly by the resiliency of the claws in a horizontal direction.

Another feature of the present division 80 relates to a means for developing axial rotation of a tooth, according to which the tooth is banded and provided at one or more points on the band (preferably at two diametrically opposite points if the axis of the tooth is to remain stationary), with projections suitable to receive resilient pressure fingers extending from bows or arches, or extensions thereof, anchored to hold them in appropriate positions; the fingers being 85 given a permanent set in directions to cause them to exert the desired pressure upon the tooth to be rotated.

The features of the invention to be particularly claimed herein will now be described in connection with the accompanying drawing, in which—

Figure 1 is a perspective view illustrating the several features of the invention as embodied in an appliance attached to a lower jaw; Fig. 2 is a similar view, showing a somewhat modified embodiment of the invention in an appliance adapted to the lower jaw; Fig. 3 is a detail view of a form of

anchoring grip having gripping claws on both sides; Fig. 4 is a horizontal section of a tooth and an anchoring grip taken in a plane immediately above the gripping claws; Fig. 5 is a front view showing the application of the open-face grip; Fig. 6 is a proximal view of the same; Fig. 7 is a perspective view of the same; Figs. 8 and 9 are, respectively, a perspective view and a side elevation of the means for developing rotation in a tooth, and Fig. 10 is a detail view of the parts shown in Figs. 1 and 2.

Referring to Fig. 1, 1 represents a bow or arch secured in position by anchoring members 2 and carrying several types of pressure devices, such for instance as the arch-shaping fingers 3, the arch-shaping bow 4, the rotating connection 5 and the occlusal bearing finger 6.

Fig. 2 shows a somewhat differently constructed carrying member 1^a adapted to lie well beyond the area of the tooth crowns and doubled upon itself to provide extensions 1^b which overlie the gums and are connected to anchorages 2 similar to those of Fig. 1, and also to anchorages 7 and 8, which are of somewhat different construction. The carrying member 1^a is provided with occlusal pressure fingers 6, as in Fig. 1, and the extensions 1^b terminate in the dental arch-shaping fingers 3. Said carrying member is also provided with a shaping bow 4, as in Fig. 1. In the embodiment Fig. 2, the bow 4 connects the extensions 1^b, near their pressure fingers 3 and thus assists in determining the positions of the latter, and, consequently, the pressure which they exert.

Fig. 2, represents a suspending hook which may be provided in any suitable numbers to prevent the movement of the appliance gingivally, which is particularly important where there are parts of the appliance which might otherwise be forced into the inter-cuspal notches sufficiently to cause separation of the teeth.

The gripping member 2 comprises the lingual bulge embracing portion 10, the connecting members 11, and the gripping claws 12. The claws 12 extend from an intermediate point in the closed loop 13 on the gripping side of the device. According to the form of anchoring grip shown at 7, the lingual bulge embracing part is provided by claws 14 extending from the intermediate portion 10^a of the closed loop on the lingual side, while the gripping side of this anchorage comprises the closed loop 13 connected by the side members 11 and carrying the gripping claws 12, as described in connection with the anchoring grip 2. The anchoring grip 8 employs the embracing loop 10 and the connecting members 11, but the gripping claws 15 on the outer side extend directly from the connecting members 11.

It thereby provides the open-face anchoring

grip. In each of the forms described, the lingual bulge embracing portion extends well toward the gum, while the connecting members overlie the inter-cuspal notches, and the gripping claws enter the embrasures 70 below the bulge in such manner that the claws have to be spread in order to permit removal of the anchoring grip. The embracing part on the lingual side cannot rise, because in so doing, it encounters a gradually increasing transverse dimension of the tooth and the device is thus held with sufficient firmness to afford proper anchorage for the carrying members connected thereto, even though the entire appliance is left 80 free for removal from the mouth of the patient at will.

The pressure bow 4 may serve as a carrying member and this part, as well as the carrying member 1, may be provided with 85 the hooked pressure fingers 16 biased, respectively, anteriorly and posteriorly in the direction of the dental arch and brought into engagement with projections 17, preferably at diametrically opposite points on 90 the band 18 which is cemented to a tooth to be rotated. The projections 17 are inclined to radii of the band 18, so as to prevent displacement of the pressure fingers while permitting the pressure fingers to be freely 95 slipped into position or intentionally removed therefrom in putting the appliance into or taking it out of the mouth.

I claim:—

1. In orthodontia appliances, an anchoring member having a lingual bulge embracing part, connecting parts in position to overlie the inter-cuspal notches, and gripping parts comprising claws adapted to enter the embrasures beneath the approximal bulge on the buccal or labial half of the tooth.

2. In orthodontia appliances, an anchoring member having a lingual bulge embracing part, connecting parts in position to 110 overlie the inter-cuspal notches, and gripping parts comprising claws adapted to enter the embrasures beneath the approximal bulge on the buccal or labial half of the tooth; said lingual bulge embracing part 115 comprising a closed loop deflected gingivally from the connecting parts.

3. In orthodontia appliances, an anchoring member having a lingual bulge embracing part, connecting parts in position to 120 overlie the inter-cuspal notches, and gripping parts comprising claws adapted to enter the embrasures beneath the approximal bulge on the buccal or labial half of the tooth; said lingual bulge embracing part 125 comprising a closed loop deflected gingivally from the connecting parts; and there being a carrying member connected with said anchoring member through the medium of said closed loop.

4. An orthodontia appliance comprising a carrying member, and posterior and anterior anchorages for said carrying member; each of said anchorages comprising a lingual bulge embracing part, connecting parts overlying the inter-cuspal notches, and gripping claws entering the embrasures beneath the approximal bulges on the buccal or labial halves of the teeth. 70
5. An orthodontia appliance comprising a carrying member, and posterior and anterior anchorages for said carrying member; each of said anchorages comprising a lingual bulge embracing part, connecting parts overlying the inter-cuspal notches, and gripping claws entering the embrasures beneath the approximal bulges on the buccal or labial halves of the teeth; the posterior anchorage members having closed loops on the outer sides with which said gripping claws are connected, and the anterior anchorage members having their claws connected directly with the connecting parts. 75
6. In an orthodontial appliance in combination, a carrying member and an open anchoring grip, said anchoring grip comprising a lingual bulge-embracing loop secured on said carrying member, a pair of claws and connecting members between said claws and said loop, said claws extending to and engaging with the buccal or labial side of a tooth. 80
7. In an orthodontia appliance, a carrying member, a plurality of anchoring members each having a lingual bulge embracing part, connecting parts and gripping parts; in combination pressure members biased to move posteriorly and anteriorly in the direction of the dental arch, and a tooth band having projections receiving said pressure members whereby axial rotation of a tooth will be developed. 85
8. In an orthodontia appliance, a carrying member, a plurality of anchoring members each having a lingual bulge embracing part, connecting parts and gripping parts; in combination pressure members biased to move posteriorly and anteriorly in the direction of the dental arch, and a tooth band having projections receiving said pressure members; said projections being located at diametrically opposite points on said band whereby axial rotation of a tooth will be developed. 90
9. In an orthodontia appliance, a carrying member, a plurality of anchoring members each having a lingual bulge embracing part, connecting parts and gripping parts; in combination a pressure member biased to exert pressure in the direction of the dental arch, and a tooth band having a projection in position to receive said pressure member whereby axial rotation of a tooth will be developed. 95
10. In an orthodontia appliance, a carrying member, a plurality of anchoring members each having a lingual bulge embracing part, connecting parts and gripping parts; in combination a pressure member biased to exert pressure in the direction of the dental arch, and a tooth band having a projection in position to receive said pressure member whereby axial rotation of a tooth will be developed. 100
11. In an orthodontial appliance in combination, a carrying member and an anchoring grip; said anchoring grip comprising a closed lingual bulge-embracing loop, an intermediate connecting portion between said loop and said member, and a pair of claws on the intermediate portion, said claws extending anteriorly and posteriorly from said intermediate portion, and engaging with the lingual half of the tooth. 105
12. In an orthodontial appliance, in combination, a carrying member and an anchoring grip; said anchoring grip comprising a closed lingual bulge-embracing loop, an intermediate connecting portion between said loop and said member, and a pair of claws secured to said loop on the labial or buccal side of the tooth, said claws extending anteriorly and posteriorly from a point on said loop situated oppositely to said intermediate portion. 110
13. In an orthodontial appliance, in combination, a carrying member and an anchoring grip; said anchoring grip comprising a closed lingual bulge-embracing loop, an intermediate connecting portion between said loop and said member, and a pair of claws on the intermediate portion, and another pair of claws secured to said loop oppositely to said first claws; said claws extending anteriorly and posteriorly from their securing points, one pair of said claws engaging with the lingual and the other pair with the buccal or labial half of a tooth. 115
14. In an orthodontial appliance in combination, a carrying member and an anchoring grip; said anchoring grip comprising a closed lingual bulge-embracing loop, an intermediate connecting portion between said loop and said member, a pair of anteriorly disposed claws on said loop and a pair of posteriorly disposed claws on said loop, one claw in each pair engaging on the lingual side, and the other claw on the buccal or labial side of the same tooth. 120
15. In an orthodontial appliance in combination, a carrying member and an open anchoring grip secured thereon and having gripping claws; said gripping claws extending through the intercuspidal notches to the buccal or labial side, and turning upon themselves so as to embrace the mesial and distal surfaces of the buccal or labial half of the tooth. 125

16. In an orthodontial appliance in combination, a carrying member and an anchoring grip; said anchoring grip comprising a part circumscribing the occlusal end of the tooth and an intermediate connecting portion between said circumscribing part and said carrying member and a pair of claws on the intermediate portion, embracing the tooth in the lingual embrasures. 70
- 10 17. In an orthodontial appliance in combination, a carrying member and an anchoring grip; said anchoring grip comprising a part circumscribing the occlusal end of the tooth and an intermediate connecting portion between said circumscribing part and said carrying member, and a pair of claws secured to said circumscribing part on the labial or buccal side of the tooth, said claws extending anteriorly and posteriorly from a 75 point on said circumscribing part opposite to said intermediate portion. 80
- 15 18. In an orthodontial appliance in combination, a carrying member and an anchoring grip; said anchoring grip comprising a part surrounding the occlusal end of the tooth, and an intermediate connecting portion between said surrounding part and said member, a pair of claws extending anteriorly from said intermediate portion and 85 said surrounding part, and another pair posteriorly, to enter respectively, the mesial and distal lingual embrasures, two of said claws impinging on the mesial and distal surfaces of the lingual half of the tooth at 90 different level from that of said surrounding part. 95
- 20 19. In an orthodontial appliance in combination, a carrying member and an anchoring grip; said anchoring grip comprising a part surrounding the occlusal end of the tooth and an intermediate connecting portion between said surrounding part and said carrying member, a pair of claws secured to said surrounding part on the labial or 100 buccal side of the tooth, and another pair of claws on the lingual side, one claw of each of said two pairs of claws extending anteriorly and the other posteriorly from a transverse plane through the axis of said intermediate portion, two of said claws entering the buccal embrasures and impinging on the mesial and distal surfaces respectively of the tooth at different level from that of 105 said surrounding portion. 110
- 25 20. In an orthodontial appliance in combination, a carrying member and an anchoring grip; said anchoring grip comprising a part surrounding the occlusal end of the tooth and an intermediate connecting portion between said surrounding part and said member, two claws, extending from said intermediate portion, one anteriorly and the other posteriorly, and entering respectively the mesial and distal lingual embrasures and 115 thereby impinging against the mesial and 120 distal surfaces of the lingual half of the tooth, two claws secured to the surrounding part on the labial or buccal side of the tooth, one of said last named claws extending anteriorly and the other posteriorly from the transverse plane through the axis of said intermediate portion and said last named claws entering the buccal embrasures and impinging respectively, on the mesial and distal surfaces of the tooth at different level 125 from that of said surrounding part. 130
21. In an orthodontial appliance in combination, a carrying member and an anchoring grip; said anchoring grip comprising a part surrounding the occlusal end of the tooth, said surrounding part being attached to the carrying member and having secured to it on the lingual side two claws extending one anteriorly and the other posteriorly to embrace the lingual half of the tooth. 85
22. In an orthodontial appliance in combination, a carrying member and an anchoring grip; said anchoring grip comprising a part surrounding the occlusal end of the tooth, said surrounding part being attached to the carrying member and having secured to it on the buccal side, two claws extending one anteriorly and the other posteriorly to embrace the buccal half of the tooth. 90
23. In an orthodontial appliance in combination, a carrying member and an anchoring grip; said anchoring grip comprising a part surrounding the occlusal end of the tooth, said surrounding part being attached to the carrying member and having two claws secured to it on the lingual side and two claws to the buccal side, two of said claws extending anteriorly and the other two posteriorly and embracing the lingual and buccal half of the tooth respectively. 95
- 28 24. In an orthodontial appliance in combination, a carrying member and an anchoring grip; said anchoring grip comprising a part surrounding the occlusal end of the tooth, said surrounding part being attached to the carrying member and having four claws secured to it near the entrance of the four embrasures, two of said claws extending buccally from the point of attachment and two lingually; each of said claws turning upon itself, cervically and then toward the central line of the dental arch so as to enter the embrasure and impinge on the gripped tooth at a point below and almost to the point of contact. 110
- 33 25. In an orthodontial appliance in combination, a carrying member and an anchoring grip; said anchoring grip comprising a portion having two double ended parts overlying the normal contact point, the four 115 ends of which parts extend buccally and lingually and turn upon themselves first, cervically and then toward the central line of the dental arch, so as to enter the embrasure and impinge on the gripped tooth at a 120
- 38 125
- 43 130

point below and almost to the point of contact—said parts to be connected by an extension from the overlying parts around the surface on one side of the occlusal end of the 5 tooth, by means of which the grip is attached to the carrying member.

The foregoing specification signed at

Washington, District of Columbia, this 14 day of September, 1912.

WILLIAM ERNEST WALKER.
